REFRIGERATING APPARATUS AND METHOD

Clara E. Quinn and John R. Lassiter, Jr., New York, N. Y., assignors, by mesne assignments, to Broquinda, Inc., St. Petersburg, Fla., a corporation of Delaware

Refiled for abandoned application Serial No. 696,160, November 1, 1933. This application July 2, 1936, Serial No. 88,696

13 Claims. (CL 62—91.5)

This invention relates broadly to improvements in refrigerating apparatus and methods of refrigerating.

5 An important object of this invention is to provide a practical and efficient refrigerant employing a primary refrigerant and a secondary refrigerant.

10 A further object of this invention is to provide an apparatus of this type, preferably but not necessarily employing solid carbon dioxide as a primary refrigerant.

15 A still further object of this invention is to provide a refrigerating apparatus having a plurality of compartments to be maintained at relatively different temperatures by means of a single refrigerant circulating in heat exchange relation therewith.

20 These and many other objects, as will appear from the following description when taken in connection with the attached drawings, are successfully obtained by means of this invention.

25 This invention resides substantially in the combination, construction, arrangement, relative location of parts, steps and series of steps, all as will be set forth in full detail below.

This application is a substitute application for application Serial No. 696,160, filed November 1, 1933.

30 Referring to the drawings, Figure 1 is a side elevational view of an apparatus in accordance with this invention;

Fig. 2 is a top plan view thereof;

Fig. 3 is a vertical cross sectional view taken approximately on the line 3—3 of Fig. 2;

35 Fig. 4 is a horizontal cross sectional view taken approximately on the line 4—4 of Fig. 3, omitting the insulation surrounding the tank 4 to show the jacket 6;

Fig. 5 is a horizontal cross sectional view taken 40 approximately on the line 5—5 of Fig. 3, omitting the insulation surrounding the tank 4 to show the jacket 6;

Fig. 6 is a vertical transverse cross sectional view taken approximately on the line 6—6 of Fig. 2;

Fig. 7 is a side elevational view with some parts broken away of the adjustable distributor;

Fig. 8 is a detail top plan view of the indicator and control knob for the distributor.

50 It is common prior art practice to employ a primary refrigerant and a secondary refrigerant circulated by thermosiphonic action between the articles or spaces to be cooled and the primary refrigerant. It is likewise well known to employ solid carbon dioxide as a refrigerant. However,

difficulties are commonly encountered in the use of solid carbon dioxide for refrigerating perishable products in spaces containing them because of the difficulty of efficiently employing solid carbon dioxide which is normally at a temperature of approximately minus 114 degrees Fahrenheit. The present invention contemplates the use of, but is not necessarily limited to the use of, solid carbon dioxide as the primary refrigerant, in conjunction with a thermo-siphonically transferred liquid secondary refrigerant. At the same time employing but a single body of such a liquid and a single mass of solid carbon dioxide, a plurality of spaces are simultaneously maintained at different temperatures.

One form of apparatus employing the present invention is illustrated in the drawings as comprising an outer casing 1 of any desired configuration and constructed of any suitable material. The outer casing 1 may, for example, be made of metal. At 2 is a heat insulating winding of any suitable and well known material having the proper thickness to effectively prevent the entry of heat into the interior of the cap. The heat insulating lining 2 is itself provided with a lining 3 of some suitable material such as tar paper, fibre, composition board, or the like. The solid refrigerant container is illustrated at 4 positioned within the cabinet so as to open exteriorly thereof, and is provided with a removable cover 5. Surrounding the lower portion of the container 4, in heat exchange relation therewith and preferably formed integrally therewith is an outer casing 6 forming a chamber designated as A therewith. It will be noted that the bottom of container 4 forms a double bottom with the bottom of container 6 and the connecting wall is provided with a plurality of openings 7 as shown. Thus the container 4 is jacketed entirely around its lower end. These parts are of course preferably made of metal or other suitable heat conducting material. Container 6 is provided with a filling pipe in which the closure plug 8 fits. At 9^a, 9^b, and 9^c are metal containers suitably distributed within the cabinet and providing spaces to contain perishable and other products to be maintained at desired low temperatures. These containers likewise open exteriorly of the cabinet and are closed by means of covers 10, 10^a, 10^b and 10^c. Surrounding the containers 9, 9^a, 9^b and 9^c respectively are the metal jackets 11, 11^a, 11^b, 11^c, respectively, forming therewith the spaces B, C, D and E respectively. These containers are provided with double bottoms as before with apertures 7. Thus in all the double 55

jacketed containers the secondary refrigerating liquid which is contained therein may pass in heat exchange relation with the bottom of the containers, as well as with the side walls.

5 At 12 is the supply conduit for the liquid secondary refrigerant for supplying this liquid from the chamber A to the bottom of the distributor 13. This distributor, as shown in Fig. 7, comprises an outer casing 14 and a telescoped inner casing 16 which are provided with spiral ridges 15 and 17 respectively. The spacing and size of the ridges is such that when the cylinders are properly aligned they will contact throughout their length so that liquid entering the space 10 between the members 14 and 16 must travel upwardly in a spiral path to reach the top of the space therebetween. The outer casing 14 is closed by means of the cover 18 through which extends a shaft 19 connected to the inner member 16. Thus the container 14 with its cover is 15 completely sealed and the inner member 16 may be rotated therein upon its longitudinal axis. Rotation thereof will vary the relative angular displacement between the sets of ridges. When 20 the inner member 16 is revolved through 180 degrees from the position shown in Fig. 7 the ridges 17 will extend at a maximum angle to the ridges 15, with the result that a liquid refrigerant may move directly upwardly in maximum volume 25 rather than spirally as when the parts are in the position shown.

Issuing from this distributor, at points which are vertically and circumferentially distributed, 30 are the pipes 24, 25, 26 and 27. These pipes extend respectively to the spaces B, C, D and E. An important feature of this invention is involved in the fact, as illustrated in the drawings, that the pipes 24, 25, 26 and 27 are of different internal bore. The internal bores of these 35 pipes are determined, all other factors being predetermined, so as to maintain a particular temperature condition within the space to be refrigerated to which they are respectively connected. Thus, for any setting of the distributor the relative 40 temperatures maintained in the containers 9, 9^a, 9^b and 9^c are fixed, but may be simultaneously varied, maintaining their relative proportions by adjusting the distributor to vary the rate of flow of the fluid from the distributor.

45 At 28 is illustrated a stand or bracket by means of which the distributor is suitably supported within the cabinet. The control shaft 19 of the distributor issues into a recess in the top of the cabinet, and is surrounded by means of a suitable protecting tube 23 so that the insulating backing 32 will not become twisted or disturbed by the rotation of the rod 19. At 20 is a dial having suitable graduations thereon which when suitably calibrated will permit of the desired adjustment of the apparatus. The control member 21 is secured to the shaft 19 by means of which the inner member 16 may be rotated. A removable cover plate 22 is provided to enclose these parts.

50 At 29 is the liquid level pipe which is provided with branches, as is clear from Fig. 4, which extend to the spaces B, C, D and E. The pipe 29 is provided with a pet cock or valve 31. This pipe extends at a level, and is connected to the jackets 55 at a level to which it is desired to maintain the liquid secondary refrigerant or heat transfer agent. Thus the liquid may be filled into the system provided by the jackets and pipe connections until it begins to overflow through the 60 pet cock 31, which should be opened through the

filling to permit the escape of trapped air. In practice the pet cock 31 will, of course, extend exteriorly of the casing so as to be readily accessible. In adjusting the apparatus for final conditions it has been found that when solid carbon dioxide or other refrigerant is introduced into the container 4, the reduction in temperature which the liquid undergoes will contract it so that its level falls below the level of pipe 29. It is desirable, therefore, to introduce further liquid 10 into the jackets to return the level under normal operating conditions to that of the pipe 29, and its branches. As previously mentioned, all the unoccupied space surrounding these elements is preferably packed with some suitable heat insulating material, which may be a fibrous material or a ground material such as ground cork. The pipes 30 connect the interior of container 4 with the space surrounding it so that when solid carbon dioxide is employed the gas resulting from 15 sublimation may escape into and saturate the entire space within the walls 3. Carbon dioxide gas is a good heat insulator, and being dry and non-injurious either to food products or the materials of which the container is made, it is 20 desirable to saturate the entire volume with its gas. Furthermore, upon its release it is at a relatively low temperature, thereby aiding in maintaining the apparatus at the proper working temperatures. This gas is evolved slowly and 25 may easily escape through the various joints between the walls 3 and the containers into the atmosphere.

At 50, 51, 52 and 53 are the return flow pipes for the secondary refrigerant. It is, of course, 30 apparent that these pipes can be united into one return flow pipe if desired. They are so proportioned in size as not to interfere with the proper free return flow of the fluid in thermo-siphonic action. It is to be noted that pipe 12 40 connects to the bottom of space A, and pipes 50, 51, 52 and 53 connect at the top of space A and spaces B, C, D and E.

Any suitable secondary refrigerant liquid may be employed. It is, of course, desirable that it 45 be liquid at all temperatures encountered in the operation of the apparatus, and that its viscosity remain sufficiently low so as not to interfere with its movement under the thermo-siphonic force encountered.

In the operation of the apparatus materials to be refrigerated, depending upon the temperatures to which they are to be maintained at, are introduced into the containers 9, 9^a, 9^b, and 9^c. The primary refrigerant such as solid carbon 55 dioxide is introduced into container 4 and all covers are replaced. The primary refrigerant absorbs heat from the secondary refrigerant in space A, thereby cooling it and increasing its density. At the same time the secondary refrigerant in the spaces B, C, D, and E is absorbing heat from the articles to be refrigerated, with the result that its density in these regions is 60 decreased.

Because of these differences in temperatures 65 and densities the liquid will flow back through pipes 50, 51, 52 and 53 into the top of space A, and at the same time the liquid will move from space A through pipe 12 into distributor 13. It will then flow through the distributor at a rate 70 depending upon its adjustment. From the distributor it will move in quantities and at rates proportional to the internal bores of the pipes 24, 25, 26 and 27 into the spaces B, C, D and E. Thus by thermo-siphonic action this liquid will 75

transfer the heat from the warmer articles to the solid refrigerant where this heat will be absorbed in transforming the solid carbon dioxide back to the gaseous state.

5 As pointed out above, the relative sizes of pipes 24, 25, 26 and 27 will be predetermined to secure the desired minimum temperature conditions within the spaces to which they are connected. The temperatures to which these spaces are 10 brought may then be simultaneously varied in unison by adjusting the distributor.

It should also be noted that the level of the secondary refrigerant in the spaces B, C, D and E is higher than the level of the liquid in space A.

15 From this description it will be apparent that we have embodied our invention in but one physical form for purposes of illustration, and that those skilled in the art will readily perceive other ways of carrying out the invention. We 20 do not, therefore, desire to be strictly limited to the disclosure as given for purposes of illustration, but rather to the scope of the appended claims.

What we seek to secure by United States Letters Patent is:

1. A refrigerating apparatus as described comprising a container for a primary refrigerant, containers providing spaces to be refrigerated, jackets individually surrounding said containers 30 and adapted to contain a liquid heat transfer medium, a supply connection from the jacket surrounding the primary refrigerant container and a plurality of branch connections extending therefrom to the jackets surrounding the containers forming spaces to be refrigerated, the internal bores of the branch connections being of different size.

2. A refrigerating apparatus as described comprising a first jacketed container and a plurality 40 of additional jacketed containers, a supply pipe extending from said first jacketed container, a distributor connected thereto and branch pipes extending from said distributor to said plurality of jacketed containers, there being one pipe connected to each jacket, the internal bores of said branch pipes being of relatively different sizes and return pipe connections extending from the jackets of said plurality of containers to the jacket of said first jacketed container.

50 3. A refrigerating apparatus including a closed circulatory system for a secondary liquid refrigerant in which the closed circulatory system comprises a plurality of jacketed containers, a main distributing pipe extending from one of said jackets, a plurality of branch pipes of different internal bores extending from said main pipe to the remaining jackets, and return pipes connecting all of said remaining jackets with said first jacket.

60 4. A refrigerating apparatus as described comprising a double jacketed container for a primary refrigerant, a plurality of double jacketed containers providing spaces to be refrigerated, a pipe connection extending from said first jacketed container, an adjustable distributor connected to said pipe, a branch pipe extending from each of the other jacketed containers to said distributor, the internal bores of said branch pipes being of relatively different diameters, and return connections from said remaining jacketed containers to said first jacketed container.

70 5. A refrigerating apparatus as described comprising a refrigerant container having double walls to provide a liquid space, a plurality of

substance containers having double walls to provide liquid spaces, a pipe extending from the liquid space of the refrigerant container, means for controlling the rate of liquid flow through said pipe connected thereto, a plurality of 5 branch pipe connections extending from said means to the liquid spaces of the substance containers, and pipe connections extending from the liquid spaces of the substance containers to the liquid space of the refrigerant container, 10 said controlling means simultaneously varying the flow of liquid through the branch pipe connections.

6. A refrigerant apparatus as described comprising a refrigerant container having double 15 walls to provide a liquid space, a plurality of substance containers having double walls to provide liquid spaces, a pipe extending from the liquid space of the refrigerant container, means for controlling the rate of liquid flow through said 20 pipe connected thereto, a plurality of branch pipe connections of different internal diameters extending from said means to the liquid spaces of the substance containers, pipe connections extending from the liquid spaces of the substance 25 containers to the liquid space of the refrigerant container, and an insulating casing surrounding all of said containers which open exteriorly thereof.

7. A refrigerating apparatus comprising a cabinet, a plurality of metal containers mounted in said cabinet and opening exteriorly thereof, a jacket surrounding each of said containers and forming therewith closed spaces, a branch connection from the jacket of one of said containers 30 to the jackets of each of the other containers, the branches being of different internal diameters and return connections from said other containers to said first container, whereby a closed circulatory system is formed and a secondary liquid 40 refrigerant in said circulatory system.

8. A refrigerating apparatus comprising a cabinet, a plurality of metal containers mounted in said cabinet and opening exteriorly thereof, a jacket surrounding each of said containers and forming therewith closed spaces, a branch connection from the jacket of one of said containers to the jackets of each of the other containers, return connections from said other containers to said first container, the branches being of different 50 internal diameters whereby a closed circulatory system is formed, a secondary liquid refrigerant in said circulatory system, and means in said branched connection for controlling the rate of flow of the liquid therethrough.

55 9. The method of varying and maintaining a plurality of spaces at different temperatures by means of a single fluid stream at a particular temperature comprising cooling the liquid to a particular temperature and dividing and thermosiphonically circulating the cooled liquid in streams of different volumes to maintain said spaces at different temperatures and varying the volume of the single stream to simultaneously 60 vary the temperatures of said spaces.

10. A refrigerating apparatus including means for cooling a secondary refrigerant liquid, a plurality of containers for holding articles to be refrigerated, means comprising conduits of different internal diameters for circulating the liquid in heat exchange relation with said containers to maintain them at different temperatures, and means for simultaneously varying the volume of fluid passing through said conduits for 70 75

simultaneously varying the temperature in said containers.

11. A device as described comprising a pair of relatively rotatable, longitudinally aligned, telescoped walls united to form a chamber, each of said walls having a helical circumferential ridge, said ridges in one position of the walls contacting to form said chamber into a helical passage, a main supply connection to the passage and a plurality of branch connections from said passage and spaced from each other and from the supply connection.

12. A device as described comprising a pair of relatively movable telescoped walls united to form a space therebetween, each of said walls having a helical ridge on its surface, said ridges facing each other and lying parallel in one position of the walls and at various angles with respect to each other in other positions of the walls, a main supply connection to the space be-

tween the walls, and a plurality of branch connections from the space between the walls, said branch connections being longitudinally distributed.

13. A device of the type described comprising a pair of telescoped cylinders, means forming with the cylinders a closed space therebetween and for holding the cylinders longitudinally aligned, said cylinders being relatively rotatable and each having a spiral ridge on the surface thereof, said ridges contacting throughout their length in one position of the cylinders and lying at various angles with respect to each other for the other positions of the cylinders, a supply connection to the space between the cylinders and a plurality of branch connections from the space between the cylinders.

JOHN R. LASSTIER, JR.

CLARA E. QUINN.
